Application October 16, 1958, Serial No. 52,998

Term of patent 14 years

(Cl. D62—2)

FIG. 1.

FIG. 2.

FIG. 3.

Fig. 1 is a view in front elevation of a colorant dispenser, showing my new design.

Fig. 2 is a top plan view of the colorant dispenser shown in Fig. 1.

Fig. 3 is another view in elevation of the colorant dispenser but taken at right angles to the view in Fig. 1.

The dominant features of my design reside in the portions shown in full lines.

I claim:

The ornamental design for a colorant dispenser, as shown and described.
